UNITED STATES PATENT OFFICE.

HARRY W. MANNING, OF PORTLAND, OREGON.

OIL-BURNER.

1,289,217.

Specification of Letters Patent. Patented Dec. 31, 1918.

Application filed March 28, 1918. Serial No. 225,238.

To all whom it may concern:

Be it known that I, HARRY W. MANNING, a citizen of the United States, and a resident of Portland, county of Multnomah, State of Oregon, have invented a certain new and useful Improvement in Oil-Burners, of which the following is a specification.

The object of my invention is to provide an oil burner of simple, durable and efficient construction.

My invention particularly concerns the burner-head and in this connection has for its purpose to so construct the latter that it will discharge a sheet of flame. This result I attain by providing the sides of the burner-head with circumferential slits instead of perforations; the latter construction having a tendency to become clogged, which interferes with the efficiency of the burner. Furthermore I make my burner-head of removable parts. My invention also has for its object the providing of a burner which shall comprise two or more burner-heads, some of which are provided with a valve by which the flow of gas into such head can be cut out, when only a single burner-head is required to be used.

Another novel feature of my invention is to provide an air-inlet for the mixing chamber of my burner and control such inlet by a valve so arranged as not to be capable of closing the inlet entirely at any time, and hence admitting some air all the time, thereby obtaining perfect combustion.

Other features of my burner are herein-after more fully described, reference being had to the accompanying drawings, in which:

Figure 1 is a front elevation of my burner;

Fig. 2 is a top view thereof;

Fig. 3 is a right-end elevation with respect to Fig. 1;

Fig. 4 is a longitudinal vertical section, centrally taken, of that of my burner-heads which is provided with a valve for cutting the same out of service, also showing a portion of the gas mixing chamber;

Fig. 5 is a diametric section of the slotted ring of my burner-head;

Fig. 6 is a plan or top view of such ring;

Fig. 7 is a fragmental elevation showing details of the air and gas mixing chamber of my burner;

Fig. 8 is a bottom view of the latter show-

ing the arrangement of the valve controlling the air inlet of said chamber;

Fig. 9 is a cross-section on the line 9—9 of Fig. 2;

Fig. 10 is a sectional detail of the generator; and

Fig. 11 is a cross-section of the generator on the line 11—11 of Fig. 1.

My burner comprises a tubular body, *a*, provided with an air-and-gas mixing chamber *b*, with which is connected the generator pipe *c*, connected at *d* to the feed pipe of the source of supply of the hydro-carbon oil. The generator *c* is provided at its end *e* with a needle orifice into the mixing chamber *b*. The mixing chamber *b* is provided at the bottom with an air inlet *e*, which is controlled by a valve *f*, preferably of the construction shown in Fig. 8; that is to say, being so constructed that it cannot at any time entirely cut off the admission of air through the inlet *e*, but to the contrary admitting some air through the same at all times, for the purpose specified. The valve *f* is regulated by a rod *g*. The mixing chamber *b* also has a removable cover or top plate *h*, so as to facilitate the cleaning thereof.

The gas in the generator pipe *c* is vaporized by the gas emitted through the slits *i* of the plate *j*. The plate has channels *k* at its side, which channels are filled with asbestos to be saturated with alcohol when first lighting the burner and heating up the generator *c*.

The body, *a*, is made with transverse baffle partitions *m*, as shown in Fig. 4, and *n*, as shown in Fig. 9, so as to retard the flow of gas and cause the efficient serving of the nearer burner as well as the distant burner. The body, *a*, is made with necks *o*, *o'*, constituting passageways or conduits for the gas into the burner-heads *p*, *p'*. The construction of the burner heads is the same

except that the dome *q* of the burner-head *p* is made with a neck *r*, in which reciprocates the stem *s* of the valve *s'*. When the latter is arranged as shown in Fig. 4, the flow of gas into the burner-head *p* would be stopped, and hence this burner-head will be cut out of service. When, however, this burner-head is to be thrown into service, the valve *s'* would be lifted and so arranged that the transverse pin *t* of the stem *s* rests on the top of the neck *r*. Each of the burner heads is made up of the following

details: The lower part *u* of the burner-head is made with a peripheral flange on which to seat a ring *v*. The ring has circumferential slits *w*, and back of these slits are integral connecting bars *x*. On the upper edge of the ring is seated the dome *q*. The slits *w* permit the flame to be emitted into a circumferential continuous sheet which produces much more effective results than in the case where the sides of the burner-head merely have perforations, and part of these perforations become blocked and prevent the gases from being emitted through such perforations, and in consequence breaking up the flame.

10 The body, *a*, has a removable elbow *y* to facilitate cleaning, the elbow being integral with the neck *b'* of the mixing chamber and being connected to the body, *a*, through 20 the medium of companion flanges *z*, bolted together.

15 3, 3 are the legs of the burner.

The core of the generator pipe, *c*, consists 25 of a number of wires *c'*, rolled as in the case of picture wire, but each wire in itself being composed of a series of wires loosely interwoven, thus causing the roll of wires to be porous and at the same time break up the gas.

30 What I claim is:

1. An oil burner of the type described, comprising a plurality of burner-heads, a gas chamber, gas passage-ways connecting the burner-heads respectively with the gas 35 chamber, the gas chamber being provided with a series of transverse baffle partitions alternately at the bottom and at the sides to thereby retard the flow of gas and provide a substantially equal feed for the nearer 40 as well as distant burner.

2. In an oil burner of the type described,

a burner head comprising a base-section provided with a peripheral flange, an intermediate section removably seated on said flange and encompassing the base, the base 45 section having a central gas passage, a dome removably seated on the intermediate section, a valve removably seated on the outlet end of said gas passage and provided with a stem extending through the cap and 50 means for supporting the valve in lifted position.

3. In an oil burner of the type described, a burner head comprising a hollow base-section, an intermediate section encompassing the base, the intermediate section being circumferentially slotted and having inwardly located narrow transverse webs connecting the parts separated by the slitting, 55 said webs adapted to space the intermediate 60 section from the encompassed wall of the base section.

4. In an oil burner of the type described, a burner head comprising a base-section provided with a peripheral flange, an intermediate section removably seated on said flange and encompassing the base, the intermediate section being circumferentially slotted and having inwardly located narrow transverse webs connecting the parts separated by the slitting, 65 said webs adapted to space the intermediate section from the encompassed wall of the base section, the base section having a central gas passage, a dome removably seated on the intermediate 70 section, a valve removably seated on the outlet end of said gas passage and provided with a stem extending through the dome, and means for supporting the valve in lifted position.

HARRY W. MANNING.
